UNITED STATES PATENT OFFICE.

WASHINGTON PAINTER, OF ALBION, ILLINOIS.

STUMP-PLOW.

SPECIFICATION forming part of Letters Patent No. 368,778, dated August 23, 1887.

Application filed June 10, 1887. Serial No. 240,927. (No model.)

To all whom it may concern:

Be it known that I, WASHINGTON PAINTER, a citizen of the United States, residing at Albion, in the county of Edwards and State of Illinois, have invented certain new and useful Improvements in Stump-Plows, of which the following is a specification, reference being had therein to the accompanying drawings.

10 This invention is an improvement on my Letters Patent No. 192,930, dated July 10, 1877; and said improvement consists, mainly, in a novel connection of the stilts and their sustaining-braces with the rear end of the 15 plow-beam, and also with the rear end of the wing of the mold-board; also in other novel features, which will be fully understood from the following description, taken in connection with the annexed drawings, in which—

20 Figure 1 is a perspective view of the improved implement, showing the diagonal brace-rod secured to the rear end of the beam and having the forked braces of the stilts secured to said beam. Fig. 2 is a plan or top 25 view of the plow, showing clearly the diagonal brace and its two binding-nuts. Fig. 3 is a side elevation of the landside of my improved plow. Fig. 4 is an enlarged vertical cross-section through the plow, taken in the 30 plane indicated by dotted line $x-x$ on Fig. 2. Fig. 5 is a perspective view in detail for the purpose of illustrating the oblong segmental slot at the rear end of the standard-shank. Fig. 6 is an enlarged cross-section on line $y-y$, 35 Fig. 5.

Referring to the annexed drawings by letter, A designates the beam of the plow, which is provided with a clevis, B, in the usual manner.

40 C C designate the stilts or handles, which are secured by a transverse bolt, h, to the beam A at their forward ends. Near the rear extremities of the said stilts the upper ends of braces D D are secured by means of a transverse bar, c, provided with nuts inside and outside. This bar with its nuts serves not only as a lateral brace, but it also serves as a tie-bar.

The lower ends of the braces D D terminate 50 in straight extensions d d, which are recessed

into the rear part of the beam A. The upper portions of the said extensions are rigidly secured to the beam A by means of a transverse bolt, d'.

It will be observed by reference to Fig. 4 55 that the lower portions of the straight ends d d are rigidly united to the plow-beam by means of the transverse part g' of a diagonal brace, G, which part is screw-threaded and provided with nuts b b, by means of which the 60 upper end of the brace G is rigidly but adjustably secured to the beam. The outer end of the brace G is bent at an angle to itself and secured to the rear extremity of the mold-board N by means of a countersunk bolt and 65 nut, g'.

The mold-board N is formed integral with a landside-section, n, which is jointed by an angular half-scarf, s', to a curved skeleton standard, R, which in horizontal cross-section 70 is U-shaped, terminating flush with the sole of the plow. The upper end of the standard R is flattened, forming a shank-bearing, r, through the front part of which passes vertically a bolt, p, which is the pivotal bolt for 75 the standard and its mold-board. In rear of this pivotal bolt is a vertical bolt, p', which passes through a slot, f', (shown clearly in Fig. 5,) through the beam, and is secured by nuts, which also binds and rigidly holds the 80 point of the plow in proper alignment with a colter, E, and the landside plane of the implement.

It will be observed by reference to Fig. 1 that the colter E is beveled at e on the sod 85 side of the plow. This colter may be secured in the same manner as described in my patent above referred to or in any other suitable manner.

In operation I am able to adjust the point 90 of the plow and to set it to take more or less land, as circumstances may require; also the adjustment can be readily made so as to fix the plow to run practically even in avoiding stumps, stones, &c.

Having described my invention, what I claim 95 as new, and desire to secure by Letters Patent, is—

The combination of a plow-beam, the handles thereof, the transverse brace c, the diagno-

nal braces D D, the lateral brace G, secured to the mold-board at one end and angular near the opposite end, passed through the lower ends of the braces D D and beam A and provided with nuts, and a plow-standard which is laterally adjustable about a front vertical axis, substantially as described.

In testimony whereof I affix my signature in presence of two witnesses.

WASHINGTON PAINTER.
